UNITED STATES PATENT OFFICE.

FRED W. WAPPAT, OF PITTSBURGH, PENNSYLVANIA.

REVERSING MECHANISM.

1,344,606.

Specification of Letters Patent. Patented June 22, 1920.

Application filed March 29, 1918. Serial No. 225,423.

To all whom it may concern:

Be it known that I, FRED W. WAPPAT, of Pittsburgh, in the county of Allegheny and State of Pennsylvania, have invented a certain new and useful Improvement in Reversing Mechanism, of which the following is a full, clear, and exact description, reference being had to the accompanying drawings, forming part of this specification, in which—

Figure 1 is an end view of a washing machine to which my mechanism is applied, a portion of a shaft casing being broken away; Fig. 2 is a side elevation of the mechanism and a vertical section of a portion of the washing machine; Fig. 3 is a front elevation of the mechanism, the casing being partly broken away; Fig. 4 is a plan view of the casing, the mechanism within the casing being indicated by dotted lines; Fig. 5 is a vertical sectional view on the line V—V of Fig. 9. Fig. 6 is a detached vertical sectional view, on the line VI—VI of Fig. 9; Fig. 7 is a side elevation of the casing, the mechanism being indicated by dotted lines; Fig. 8 is a detached elevation of the clutch shifting mechanism; Fig. 9 is a plan view of the mechanism, the casing being in section; Fig. 10 is a detached view partly in section of the wringer clamp; Fig. 11 is a plan view of the slotted plate through which the starter shaft passes; and Fig. 12 is a detached view, partly in section, of a portion of the mechanism by which the reversing clutch may be thrown by hand.

My invention relates to driving and reversing mechanism and particularly to such mechanism when used for driving and reversing the drums of washing machines. The object of my invention is to provide driving and reversing mechanism of simple construction, positive in its action, durable, simple to operate, and which may be so connected to the washer as to avoid the liability of grease and dirt entering therein; and it consists in the parts and operation of parts hereinafter more fully described.

In the drawings a portion of the body of the washing machine is indicated at 2, one end of the frame of the washer being shown in Fig. 1, which also shows a swinging wringer mounted on the body of the washing machine.

The driving and reversing mechanism is mounted on one of the end frames of the washer in a casing 3, and is inclosed therein

by the cover 4. The power can be derived from any suitable source, shown in the drawings as an electric motor 5, mounted upon the base portion of the frame of the washing machine. As shown, the power shaft 6 of this motor extends into the lower portion of the casing 3, being connected with the armature shaft 7 of the motor by a suitable worm and worm gear which is not shown in the drawings, but which is inclosed in the casing 3, and may be of any suitable construction. Joints of suitable construction, as indicated at 6', may be made in the shafts 6 and 7 to permit proper alinement of the shafts. At the upper end of the power shaft 6 within the casing 3 is a bevel gear 9, which meshes with a bevel gear 10, which is connected to a miter clutch gear 11 loosely mounted on the intermediate shaft 12 within the casing 3. Slidably keyed to the shaft 12 is a clutch member 13, which is provided with jaws or lugs 14 and 14', one on each side of the same, the lug 14 being adapted to engage with the lug 15 on the face of the gear 11 and the lug 14' being adapted to engage with the lug 15' on the face of the gear wheel 16, which similarly to the gear wheel 11 is loosely mounted on the shaft 12. Meshing with each of the gears 11 and 16 is the bevel gear 55 which is keyed to the vertical shaft 56. This gear 55 causes the rotation of the gear 16 on the shaft 12 in the opposite direction to that of gear 11. At the inner end of the shaft 12, and keyed thereto, is a bevel gear 17, which meshes with a beveled gear 18 on the gear wheel 19, which is loosely mounted on the drum or cylinder shaft 20. Keyed to the shaft 20 is an arm 21, provided with a stud 22 extending from the inner face of the same, and provided with a rubber ring or other resilient member 23. This stud and ring fit within pockets 24 and 24' in the web of the bevel gear 19, the rubber ring serving as a shock absorber, and the pocket 24' engaging with the ring serving to impart the power from the bevel wheel 19 to the arm 21.

which is keyed to the shaft 20, the shaft 20 being connected with the drum or cylinder 25 by means of an arm 26 and clutch 27, the arm being keyed to the shaft 20 and the clutch 27, which is fastened to the cylinder 25, engaging with the arm 26. This shock absorber is not claimed herein but is claimed in my application Serial No. 292,854, filed April 26, 1919. Loosely mounted on the

shaft 20 is an arm 28 in which arm, and fixed thereto, is a shaft 29, loosely mounted on which shaft is a stop or intermittent gear 30, which is in the form of a star wheel, 5 having in this case six teeth or stops, the number of stops being optional, but necessarily corresponding to the number of revolutions the drum must make before it is reversed. On the inner face of the star wheel 10 30 is a lug 31, which is adapted to engage with a lug 32 on the adjacent face of the arm 28. Extending from the hub of the gear 19 is a tooth 33, which at every revolution of the gear 19 engages with one of the 15 teeth of the star wheel 30, and imparts to the star wheel the sixth of a revolution, and the lug 31 on the star wheel having come in contact with the lug 32 of the arm 28, carries the arm, at the sixth revolution of the 20 gear 19, in the direction in which the gear is turning. On the end of the arm 28 is a weight 35 above the shaft 29. Slotably connected with the shaft 29 is a pivoted arm 36, the shaft 29 passing through the slot 37, and 25 at its inner end the arm 36 is pivoted in a clevis 38 on the end of a reciprocating shaft 39, which shaft is slidably journaled in a socket 40, extending from the casing 3, and is also journaled in the partition 41 of the casing. Keyed to the shaft 39 is a yoke member 42, which embraces the clutch 13, engaging with the annular rings thereof, and is adapted to throw the lugs 14, 14' into and out of the line of passage of the lugs 15 and 15'. 30 Mounted upon a collar 43, which is a part of or fixed to the casing 3, is a collar or member 44, which is part of or fixed to the operating lever 45, which extends up over the top of the casing 3. Keyed to the collar 44, and extending down loosely through the 35 collar 43, is a shaft 46, to the lower end of which shaft is keyed a yoke arm 47, which engages with a pin 48, which is keyed to the shaft 39 in such manner that by movement 40 of the lever 45 the shaft 39 shall reciprocate longitudinally to operate the clutch 13 through the yoke 42. At the outer end of the lever 45 is a collar 49 in which is a rotatable spring-pin 50, having a lug 51 adapted to fit in a recess in the collar 49, and surrounding the pin 50 within the collar 49 is a spring 52, which tends to normally keep the pin in its lower position, but allowing the pin 50 to be raised and turned to engage 45 the lug 51 with the upper edge of the collar 49 to hold the pin in its elevated position. On top of the casing 3 is a plate 53 secured by suitable bolts passing through slots 54, the purpose of the slots being to permit of the 50 easy adjustment of the plate. Extending through the plate 53 is a pocket 55, within which the lower end of the pin 50 is adapted to engage when the lever 45 is brought to its intermediate or neutral position. 55 The vertical shaft 56, which extends up-

wardly from gear 55 through a boss 57, which is secured to the casing 3 at its upper end, is provided with a recess 58, within which a tongue of the wringer shaft is adapted to engage, the wringer shaft being 60 inclosed in the pipe 59, at the top of which pipe is a ratchet collar 60, which is secured to the frame 2 of the machine, and in which collar the pipe 59 is rotatable to enable the wringer to be swung by hand to the desired 65 position. The driving mechanism of the wringer is contained in a casing 61, to which is secured a pivoted pawl 62 adapted to engage with the teeth of the collar 60, the purpose of the pawl being to prevent the swinging of the wringer should the operator neglect to clamp it, which clamping is accomplished by means of the clamp 63, which bears against the pipe 59, and is operated by a bell crank lever 64, as shown in Fig. 10. 70 75 80 85

The operation is as follows: The mechanism being in the neutral position shown in Fig. 3, the motor 5 having been started, which causes the rotation of the gears 11 and 16 loosely in opposite directions on the 90 intermediate shaft 12, the power is imparted in either direction to the drum 25 by throwing the clutch 13 into connection with either of the gears 11 and 16, which is accomplished by moving the arm 45 by hand, 95 which turns the shaft 46, and through the yoked arm 47 throws the shaft 39 longitudinally, which moves the clutch 13 against one or other of the gears 11 and 16, thus imparting power through the gear and clutch 100 100 to the shaft 12, to which shaft the clutch is keyed. The rotation of the shaft 12 also causes the rotation of the gear wheel 19, which through the lug 24 of the arm 21 causes the rotation of the shaft 20 and consequently the rotation of the drum 25 to 105 which the shaft is connected. As the shaft completes its revolution the tooth 33 comes in contact with a tooth of the star wheel 30, giving it one-sixth revolution, and this is repeated until the star wheel makes a complete revolution, when the lug 31 of the star wheel, having previously engaged with the lug 32 on the face of the arm 28, locks the arm and the gear 19 with each other, 110 and causes the arm 28 to be thrown on its pivot in the direction in which the gear 19 is rotating, which brings the shaft 29 in contact with the end of the slot 37, and moves the arm 36 and shaft 39 sufficiently 115 120 to carry the clutch 13 to its neutral position between the gears 11 and 16, thus cutting off power from the shaft 12 to the shaft 20. But, as this throws the weighted arm 28 off its center of gravity, the force of gravity 125 throws the arm 28, the arm 36, and shaft 39 sufficiently to bring the clutch 13 into contact with the opposite gear, 11 or 16, which restores power to the shaft and causes the shafts 12 and 20 to move in a reverse direc. 130

tion, thus imparting a reverse movement to the drum through the shaft 20, and, also, to the star wheel 30, which, after making a complete revolution, the lug 31 coming in contact with the opposite side of the lug 32, again locks the arm 28 with the gear 19, and carries the same in the direction in which the gear 19 is then traveling, thus again bringing the arm 28 first to a vertical and then to the reverse inclined position. When it is desired to stop the operation of the washer, the arm 45 is brought to its central or neutral position by the hand of the operator, whereby the clutch 47 carries the shaft 39 and the clutch 13 to a neutral position between the two gears 11 and 16.

During the normal operation of the washer the control arm 45 moves from side to side with each reversal of the mechanism, and at the time of passing the central position, the door of the drum is always at the top so that at any time it is desired to stop the washer to obtain access to this door, for the introduction or removal of clothes, this may be done automatically by turning the pin 50 until the lug 51 is over the recess in the collar 49, which causes the spring to force the pin against the plate 53, and as the pin reaches the pocket 55 within the plate, to drop therein, which prevents the force of gravity on the arm 28 carrying the clutch 13 into contact with the opposite gear wheel.

The purpose of the stud 24 fitting loosely in the pocket 24' is to act as an auxiliary connection between the gear 19 and stud should the ring 23 become worn or otherwise defective. The operation of the drum may be stopped at any time by throwing the arm 45 by hand to its middle or neutral position.

It should be noted that the apparatus I have described is simple, compact, positive in its action, and that it is practically out of contact with the body of the washer, and inclosed in a carrier, so that there is no liability of grease and dirt passing from the apparatus to the cylinder or drum within which the clothes are washed, or of dirt or dust obtaining lodgment within the mechanism. It should also be noted that the power gears 11 and 16 and the clutch 13 are contained in a closed chamber *a* of the casing 3, and separated from the other parts of the mechanism by the partition 41. This permits of the use of a body of grease or other lubricant surrounding the gears and clutch which prevents wear of these parts. It should also be noted that the use of springs and other mechanism liable to rapid deterioration, is avoided, and that the reversing arm being actuated first by the star wheel to release the clutch 13, and then by the force of gravity to engage the clutch with the opposite gear, thus serves to take

up any lost motion resulting from wear on any of the bearings. Owing to this construction it is unnecessary to use lubricant other than directly about the bearings in the chamber *b* of the casing 3. 70

In place of the weight 35 on the arm 28 other force applying devices, such as would suggest themselves to one skilled in the art, may be employed to complete the throw of the arm, but I prefer to employ 75 the force of gravity as has been described.

Having thus described my invention, what I claim and desire to secure by Letters Patent is:

1. The combination with a power shaft, 80 of a reversing clutch thereon, oppositely rotating means arranged to be alternately clutched to said power shaft, and means to throw said clutch comprising a shaft driven by the power shaft, a weighted arm idly mounted on the driven shaft, a pin carried by the arm, a star wheel mounted on the pin, a lug on the driven shaft adapted to engage and move the star wheel a part of a rotation at each rotation of the driven 85 shaft, a lug on the arm adapted to engage a coöperating lug on the star wheel at each revolution thereof whereby to lock the star wheel to the arm and cause the arm to be driven, and a shaft connected to the arm 90 at one end and to the reversing clutch at the other, whereby when the arm is driven the clutch is reversed.

2. The combination with a power shaft, 100 of a driven shaft, transmission means between said shafts, oppositely driven gears on the power shaft, a clutch arranged to engage one or more of said gears, a periodic reversing mechanism for said clutch comprising a weighted arm idly mounted 105 on the driven shaft, a connection from said arm to the clutch, a star wheel mounted on said arm, means for step-wise rotating said star wheel at each rotation of the driven shaft, and means to lock said star wheel to 110 said arm at each complete rotation of the star wheel and thus cause the arm to be driven through the connection therefrom to the clutch, to shift said clutch.

3. In reversing mechanism, the combination of a power shaft, oppositely driven gears thereon, a reversing clutch splined to said shaft and arranged to engage said gears alternately, a driven shaft geared to the driving shaft, a gear on said driven shaft 120 and provided with a lug, a star-wheel the teeth of which are arranged to engage with the lug on said gear and itself being provided with a lug, an arm provided with a lug arranged to engage with the lug on the 12. star-wheel, a reciprocating rod connected to the arm, and a clutch shifting yoke connected to said rod.

4. In reversing mechanism, the combination of a power shaft, oppositely driven 130

- gears thereon, a reversing clutch on said power shaft arranged to engage said gears alternately, a gear on said power shaft, a driven shaft, a gear thereon meshing with 5 the gear on the power shaft, said driven gear being provided with a lug, a star-wheel, the teeth of which are arranged to be engaged by the lug on said driven gear and itself being provided with a lug, a 10 weighted arm provided with a lug arranged to be engaged by the lug on the star-wheel, a shaft carried by said arm and upon which the star-wheel is journaled, a reciprocating rod having a slotted operative connection 15 with the shaft of the star-wheel, and a clutch shifting yoke connected to said reciprocating rod.
5. In reversing mechanism, the combination of a driving shaft, a driven shaft, transmission means between said shafts, a clutch splined to the power shaft and arranged to engage one or the other of said gears, a periodic reversing mechanism for the clutch comprising a reciprocating shaft connected 20 to the clutch, mechanism connecting said reciprocating shaft to the driven shaft and arranged to operate said reciprocating shaft after a predetermined number of rotations of the driven shaft, a hand lever, and connections therefrom to said reciprocating shaft, whereby to operate said clutch by hand.
6. In reversing mechanism, the combination of a driving shaft, a driven shaft, transmission means between said shafts, a clutch splined to the power shaft and arranged to engage one or the other of said gears, a periodic reversing mechanism for the clutch comprising a reciprocating shaft connected 25 to the clutch, mechanism connecting said reciprocating shaft to the driven shaft and arranged to operate said reciprocating shaft after a predetermined number of rotations of the driven shaft, a hand lever, and connections therefrom to said reciprocating shaft, whereby to operate said clutch by hand.
7. Reversing mechanism, comprising in combination, a power shaft, a driven shaft, transmission means between said shafts, oppositely driven gears on the power shaft, a clutch splined to the power shaft and arranged 30 to engage one or the other of said gears, a periodic reversing mechanism for the clutch comprising an arm idly mounted on the driven shaft, a connection from said arm to the clutch, and means to lock the 35 arm to the driven shaft after a predetermined number of rotations thereof in either direction.
8. Reversing mechanism, comprising in combination, a power shaft, a driven shaft, transmission means between said shafts, oppositely driven gears on the power shaft, a clutch arranged to connect said gears with the power shaft alternately, means to throw 40 said clutch comprising an arm idly mounted on the driven shaft in raised position, means to lock the arm to the driven shaft after a predetermined number of rotations thereof in either direction, a pin on said arm, and a reciprocating rod having a slotted connection to said pin and connected to the 45 reversing clutch.
9. Reversing mechanism, comprising in combination, a driving shaft, a driven shaft, transmission means between said shafts, oppositely driven gears on the power shaft, a clutch arranged to connect said gears to 50 the power shaft alternately, means to throw said clutch comprising an upwardly extending weighted arm pivotally mounted on the driving shaft, a reciprocating member having a slotted connection to said pin and operatively connected to the clutch, and means to lock said arm to the driven shaft after a predetermined number of rotations thereof in either direction and thereby move 55 the weighted arm through its vertical position to cause it thereafter to actuate the clutch.
10. Reversing mechanism, comprising in combination, a power shaft, a driven shaft, transmission means between said shafts, oppositely driven gears on the power shaft, a clutch arranged to connect the said gears to 60 the power shaft alternately, means to actuate said clutch comprising a weighted arm idly mounted on the driven shaft, a pin on said arm, a reciprocating member connected to the reversing clutch and having a slotted connection to the pin on said arm and serving to hold said arm in upwardly 65 extending position, and means to intermittently lock said arm to the driven shaft and thereby cause said arm to be carried through its upright vertical position to permit the weight thereof to move said reciprocating member to throw the reversing clutch.
- In testimony whereof I have hereunto set my hand.

FRED W. WAPPAT.
